UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MEANS FOR TREATING MATCH-SPLINTS WITH POWDERED MATERIAL.

1,313,472.

Specification of Letters Patent.

Patented Aug. 19, 1919.

Application filed January 12, 1918. Serial No. 211,678.

To all whom it may concern:

Be it known that I, JOSEPH C. DONNELLY, a citizen of the United States, and resident of Barberton, in the county of Summit and State of Ohio, have invented certain new and useful Improvements in Means for Treating Match-Splints with Powdered Material, of which the following is a specification.

10 This invention relates to means for treating match splints with powdered material, such as ammonium phosphate, adapted to render the splints non-glowing when they have been ignited and the flame extinguished.

15 The object of my invention is to provide for the economical, efficient and uniform application of powdered anti-glowing material to and throughout the exposed surfaces of 20 match splints during the operation of a match making machine employing a traveling carrier by means of which rows of splints are supported in spaced relation to each other.

25 The invention, broadly considered, comprises a structure wherein the powdered anti-glowing material is fed in a compact stream to and along the path of the splints as they progress with the splint carrier of the match 30 machine.

35 The invention also comprises a structure including two chambers whereof one constitutes an "impregnating" chamber which is arranged in the path of the splints on the carrier, and the other constitutes a supply chamber for powdered anti-glowing material, and means for establishing a continuous 40 circulation of the said material through the two chambers in such a manner that the powder is forced in a compact stream to and along the impregnating chamber and into intimate contact with the traveling splints.

45 The invention also comprises various novel features of construction and combinations of parts which will be hereinafter described, and the scope of the invention then be defined in the appended claims.

In the drawings—

Figure 1 is a plan of an apparatus embodying the principle of my invention, part of the hood at the forward end of the casing being broken away to expose the internal construction.

Fig. 2 is a longitudinal vertical section of 55 the apparatus and a portion of the splint

carrier associated therewith, a portion of the paraffin tank through which the splints progress after they leave the said apparatus, being indicated in dotted lines.

Fig. 3 is a partial transverse section through the gearing for driving the inclined screw-conveyers, as on the line 3—3 of Fig. 2.

Fig. 4 is a similar section, on a plane through the hood, as on the line 4—4 of Fig. 2.

Fig. 5 is a similar section, on a plane through the supply chamber, as on the line 5—5 of Fig. 2.

Fig. 6 is a partial longitudinal vertical section through the vibratory mechanism for the splint carrier, as on the line 6—6 of Fig. 2.

Referring to the drawings, 10 designates a portion of an endless carrier of any known or approved type into which the splints are inserted in consecutive rows and are thus transported in spaced relation to each other throughout the match-making path. Suitably-located in the route of the carrier, after it leaves the splint-inserting station, and before it reaches the paraffin tank 11, is a structure which presents an inclined "impregnating" chamber 12, so-called, to the path of the splints. Anti-glowing material, such, for example, as finely-divided ammonium-phosphate, is delivered to this chamber and advanced therealong in intimate contact with the splints, thereby coating or "impregnating" the splints and imparting thereto the desired non-glowing property.

The said structure in its preferred form comprises a casing of appropriate size and shape which provides, in addition to the impregnating chamber 12, a lower powder supply chamber 13, and an inclined feed-chamber 14 extending upwardly from the supply chamber to and communicating with the upper end of the impregnating chamber. The lower end of the latter chamber communicates directly with the supply chamber.

In the present instance the casing includes two spaced side walls 15; an inclined rearward wall 16; and a vertical forward wall 17 terminating at its upper end in an inclined bottom portion 18; the whole being supported on a hollow base 19. Between the side walls 15, near the top of the casing, is a transverse division member 20, the top of which is inclined downwardly from front 110

to rear to constitute the floor of the impregnating chamber. The underside of this member comprises two downwardly converging portions, whereof the front portion is in spaced parallel relation to the inclined portion 18 of the casing, thus providing throughout the internal width of the latter the inclined feed-chamber 14. A chambered member or hood, 21, establishes communication between the upper end of the feed-chamber and the adjacent end of the impregnating chamber, thus permitting the transference of a compact stream of material from the feed chamber to and along the impregnating chamber. The lower end of the division member 20 terminates some distance in front of the end wall 16 of the casing, thereby affording a clear passage for the material from the impregnating chamber to the supply chamber.

The preferred means herein illustrated for circulating the material through the chambers, including the impregnating chamber, comprises two inclined counterpart screw conveyers 22 which are disposed in spaced relation to each other within the feed chamber. These conveyers extend down into the supply chamber and their lower ends are journaled in boxes in the rearward end wall 16 of the casing. The upper ends of the cores or spindles of the conveyers extend into and through the hood 21 and are journaled in spaced bearings 23 in a forwardly extending frame 24 on the hood. The conveyers may be rotated in any suitable manner. In the present instance the upper spindle extension of each of the conveyers is equipped with a helical gear wheel 25 in mesh with a similar wheel 26 on a transverse shaft 27 having its bearings in boxes 28 forming a part of the frame 24, whereby when the shaft 27 is properly rotated from a suitable source of power, (as, for example, an electric motor geared with the shaft) the two conveyers are concurrently driven, and the material is thereby transferred from the supply hopper into the feed chamber and thence into the hood. The elevating screw threads 29 of the conveyers terminate at or adjacent the entrance to the hood, and each conveyer is preferably provided adjacent the forward end of the hood with one or more threads 30 reversely pitched with respect to the lower threads. The threads 30 act in opposition to the threads 29 upon the material as it enters the hood, thereby crowding the banked material toward the top of the hood and, perforce, into the upper end of the impregnating chamber. Such material is thus forced to flow in a compact stream along the impregnating chamber and into the path traversed by the depending splints in said chamber. Part of this flowing material adheres to the surfaces 65 of the splints and the remainder progresses

to the rearward end of the impregnating chamber, whence it drops into the supply chamber. In this way continuous circulation of the powder within the casing, including the impregnating chamber, is effected.

The carrier may be supported and guided in its travel to and past the casing in any suitable manner. In the present instance said carrier is supported by parallel guide rails 31 which are suitably curved to effect the gradual descent of the splints into the upper end of the impregnating chamber; thence direct the splints along the chamber to its lower end, thence out of the chamber and over the lower end of the structure. The rails 31 are spaced apart to support the respective edges of the carrier plates, and are connected at intervals by cross-bars 32, thus constituting a unitary frame. Ledge strips 33 are preferably affixed to the rails 31, adjacent the impregnating chamber, so as to overhang the edges of the carrier and insure its proper travel in relation to the chamber. The rails are provided at their lower portions with depending lugs 34 which are pivoted to brackets 35 on the lower end of the casing. The upper portions of the rails are pivotally connected by arms 36 with eccentrics 37 on a shaft 38 in rear of and parallel with the drive shaft 27; the two shafts being equipped with intermeshing gear wheels 39, 40 respectively. The ratio of the gearing is such that the shaft 38 is driven at a relatively high speed; and hence through the eccentric connections between said shaft 38 and the rails the latter and therewith the proximate portion of the traveling carrier and its depending splints, are rapidly vibrated. The vibratory movement of the splints produces an up and down rubbing thereof against the mass of powder within the impregnating chamber, which action in conjunction with the advancement of the splints and the material along the impregnating chamber insures a thorough and effective treatment of the splints with the powdered material.

I preferably divide the impregnating chamber into two compartments by means of a median longitudinal division wall 41 which is so located as not to obstruct the passage of the splints during the progress of the carrier. This wall insures a more uniform distribution of the powder throughout the chamber.

While I have herein illustrated two inclined conveyers for raising the powder from the supply chamber to the receiving portion of the impregnating chamber, and forcing it in a compact stream along the latter, it is to be understood that a single conveyer, or a series of three or more conveyers, may be employed.

The powder may be introduced into the supply chamber in any suitable manner.

In the present instance a hopper 42 arranged at one side of the structure communicates with the supply chamber through an opening or channel 43 in the adjacent side wall. A screw conveyer 44 extends transversely of the chamber and into and across the lower portion of the hopper, such conveyer having reversely-inclined threads 45 extending in opposite directions from or adjacent the middle of the chamber, as shown. One end of the spindle of this conveyer extends outwardly beyond the casing and bears a fast pulley 46 which may be driven from a suitable source of power. Powder poured into the hopper will be carried by the conveyer 44 into the supply chamber and therein agitated and moved to and fro into the paths of the respective inclined conveyer screws 22 by the action of the reversely inclined screws 45. Thus the powder will be prevented from banking up at the sides of the supply chamber. The several screws operate to break up the material and maintain it in a finely-divided condition.

The supply chamber 13 is preferably provided with a movable bottom 47, which may be opened to permit the contents of the chamber to fall into the hollow base or pit below the chamber, as occasion may require.

It is to be noted that all the journals and gears are suitably located and incased to preclude the passage of the powder thereto.

It is to be understood that I do not limit myself to the specific details of construction disclosed, as the same may be variously modified within the principle of my invention and the scope of the appended claims.

I claim—

1. In a match machine having a splint carrier constructed to support rows of splints in spaced relation to each other, a structure comprising a chamber into which the splints depend during a part of their travel, and means for feeding a compact stream of anti-glowing powder into said chamber and along with said splints during their travel.
2. In a match machine having a splint carrier constructed to support rows of splints in spaced relation to each other, a structure comprising a chamber into which the splints depend during a part of their travel, an underlying chamber for a supply of anti-glowing powder, said latter chamber being in communication with the respective ends of the first-named chamber, and means for establishing a continuous circulation of the material through the two chambers, said means delivering the material in a compact stream to and causing it to flow through said first-named chamber and along with the splints therein.
3. In a match machine having a splint carrier constructed to support rows of splints in spaced relation to each other, a structure comprising a chamber into which the splints

depend during a part of their travel, an underlying chamber for a supply of anti-glowing powder, said latter chamber being in communication with the respective ends of the first-named chamber, and screw-conveyer 70 means for transferring the powder in a compact stream from the underlying chamber to the forward end of and along the first-named chamber, whereby a continuous circulation of the powder through the two chambers 75 and along with the splints in the first-named chamber is effected.

4. In a match machine having a splint carrier constructed to support rows of splints in spaced relation to each other, a structure 80 comprising a chamber into which the splints depend during their travel, an underlying supply chamber for anti-glowing powder, a feed chamber inclining upwardly from the latter chamber toward and communicating 85 with the forward end of the first-named chamber; a screw conveyer mounted to rotate within said supply and feed-chambers, and means for rotating said conveyer whereby the powder is transferred from the supply 90 chamber to the first-named chamber and forced therethrough in contact with the splints therein.

5. In a match machine having a splint carrier constructed to support rows of splints 95 in spaced relation to each other, a structure comprising a chamber into which the splints depend during their travel, an underlying supply chamber for anti-glowing powder, a feed chamber inclining upwardly from the 100 latter chamber toward and communicating with the forward end of the first-named chamber, a screw-conveyer mounted to rotate in said supply and feed-chambers, and means for rotating said conveyer, said conveyer 105 having an elevating thread throughout the greater part of its length and having adjacent the forward end of the first-named chamber a thread pitched reversely of the elevating thread.

6. In a match machine having a splint carrier constructed to support rows of splints in spaced relation to each other, a structure comprising a casing having therein a main supply chamber, an inclined feed-chamber extending upwardly therefrom, an impregnating chamber overlying the feed chamber and arranged in the path of the splints on the carrier, a hood providing communication between the upper end of the feed chamber and the forward end of the impregnating chamber, and means for feeding anti-glowing powder from the supply chamber to the impregnating chamber by way of the feed chamber and the hood.

7. In a match machine having a splint carrier constructed to support rows of splints in spaced relation to each other, a structure comprising a casing having therein a main supply chamber, an inclined feed-chamber 125 130

- extending upwardly therefrom, an impregnating chamber overlying the feed chamber and arranged in the path of the splints on the carrier, a hood providing communication between the upper end of the feed chamber and the forward end of the impregnating chamber, an inclined screw conveyer mounted to rotate in said supply and feed chambers, and means for rotating said conveyer.
10. 8. In a match machine having a splint carrier constructed to support rows of splints in spaced relation to each other, a structure comprising a casing having therein a main supply chamber, an inclined feed-chamber extending upwardly therefrom, an impregnating chamber overlying the feed chamber and arranged in the path of the splints on the carrier, a hood providing communication between the upper end of the feed chamber and the forward end of the impregnating chamber, an inclined screw conveyer mounted to rotate in said supply and feed chambers, and means for rotating said conveyer, together with a powder supply hopper and a screw conveyer extending therefrom into and transversely of the supply chamber, said latter conveyer having reversely - pitched threads.
15. 9. In a match machine having a splint carrier constructed to support rows of splints in spaced relation to each other, a structure comprising a casing having therein a main supply chamber, an inclined feed chamber extending upwardly therefrom, an impregnating chamber having a plurality of longitudinally - extending compartments overlying the feed chamber and arranged in the path of the splints on the carrier, a hood providing communication between the upper end of the feed chamber and the forward end of the impregnating chamber, a plurality of inclined screw conveyers mounted to rotate within said supply and feed chambers, and means for rotating said conveyers, said conveyer having an elevating screw terminating adjacent to the inlet portion of the hood and having within the hood a thread pitched reversely of and spaced from the elevating thread.
20. 10. In a match machine having a splint carrier constructed to support rows of splints in spaced relation to each other, a structure comprising a casing having therein a main supply chamber, an inclined feed chamber extending upwardly therefrom, an impregnating chamber having a plurality of longitudinally - extending compartments overlying the feed chamber and arranged in the path of the splints on the carrier, a hood providing communication between the upper end of the feed chamber and the forward end of the impregnating chamber, a plurality of inclined screw conveyers mounted to rotate within said supply and feed chambers, and means for rotating said conveyers.
25. 11. In a match machine having a splint carrier constructed to support rows of splints in spaced relation to each other, a structure comprising a casing having therein a main supply chamber, an inclined feed chamber extending upwardly therefrom, an impregnating chamber having a plurality of longitudinally - extending compartments overlying the feed chamber and arranged in the path of the splints on the carrier, a hood providing communication between the upper end of the feed chamber and the forward end of the impregnating chamber, a plurality of inclined screw conveyers mounted to rotate within said supply and feed chambers, and means for rotating said conveyers.

carrier constructed to support rows of splints in spaced relation to each other, a structure comprising a casing having therein a main supply chamber, an inclined feed chamber extending upwardly therefrom, an impregnating chamber having a plurality of longitudinally - extending compartments overlying the feed chamber and arranged in the path of the splints on the carrier, a hood providing communication between the upper end of the feed chamber and the forward end of the impregnating chamber, a plurality of inclined screw conveyers mounted to rotate in said supply and feed chambers, and means for rotating said conveyers, together with a powder supply hopper and a screw conveyer extending therefrom into and transversely of the supply chamber, said latter conveyer having reversely - pitched threads.

11. In a match machine having a splint carrier constructed to support rows of splints in spaced relation to each other, a chamber arranged in the path of the splints on the carrier, means for feeding a compact stream of anti-glowing material along said chamber, and means for effecting relative vibratory movement between the carrier and the chamber when the splints are traversing the latter.

12. In a match machine having a splint carrier constructed to support rows of splints in spaced relation to each other, a chamber, means for feeding anti-glowing material along the same, means for supporting and guiding the carrier adjacent said chamber whereby the splints on the carrier are caused to progress through the said chamber, and means for vibrating said supporting and guiding means during the travel of the carrier.

Signed at Barberton in the county of Summit and State of Ohio this 4th day of January A. D. 1918.

JOSEPH C. DONNELLY.
